ROLLER SKATE AND CARRIER DEVICE THEREFOR

Filed June 10, 1947

UNITED STATES PATENT OFFICE

2,531,959

ROLLER SKATE AND CARRIER DEVICE
THEREFORArthur Woodard and Irving W. Lewine,
New York, N. Y.

Application June 10, 1947, Serial No. 753,612

2 Claims. (Cl. 289—11.37)

1 This invention relates to skates and means thereon for illuminating an area below the skate.

An object of this invention is to provide a skate and a device mounted on the underside of the skate and provided with spring clips, and a battery operated flash light removably mounted on the spring clips, the arrangement being such that the illumination is directed downwardly and forwardly relative to the skate, whereby to produce highly attractive illumination as the skater skates around.

Another object of this invention is to provide highly improved illuminating means detachably attachable to the underside of a roller skate or ice skate, and comprising a clamp engaging the skate and provided with spring clips, a battery casing releasably mounted on the spring clips and being provided with a socket to receive the base of a flashlight lamp, and being inclined forwardly and downwardly so that when a flashlight lamp is screwed into the socket, light beams therefrom will be directed forwardly and downwardly relative to the skate to illuminate the floor or ground beneath and forwardly of the skate.

Still another object of this invention is to provide a strong, rugged and durable device of the character described, which shall be attractive in appearance, relatively inexpensive to manufacture, and practical and efficient to a high degree in use.

Other objects of this invention will in part be obvious, and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown various possible illustrative embodiments of this invention:

Fig. 1 is a side elevational view of a shoe attached roller skate provided with illuminating means embodying the invention;

Fig. 2 is a bottom plan view of the structure shown in Fig. 1;

Fig. 3 is a cross-sectional view taken on line 3—3 of Fig. 1;

Fig. 4 is a longitudinal cross-sectional view taken through the illuminating means and part of the skate to which it is attached, and illustrating a modified construction; and

Fig. 5 is a cross-sectional view taken on line 5—5 of Fig. 6;

2 Fig. 6 is a view similar to Fig. 4, but illustrating the illuminating means on another type of skate.

Referring now in detail to the drawing, for one illustration of the invention, 10 designates a shoe attached roller skate. Numeral 11 designates the shoe, attached to the skate. The skate 10 comprises a top wall or platform 12 and an under reinforcing strip 12a riveted thereto by rivet 13. Extending downwardly from the platform 12 are front and rear axle supports 14, supporting axles 15 which carry the wheels 16. Each support 14 comprises inner upwardly and inwardly inclined struts 14a and outer, outwardly and upwardly inclined struts 14b. At the underside of the skate and interconnecting the front and rear inner struts 14a, is a frame member 16a, comprising an upwardly and rearwardly inclined strap 17, a top portion 18 extending therefrom and connected to the platform 12, and under support 12a by said rivet 13, and a rearwardly and outwardly inclined strap 19 connected to the rear inner axle supporting strut 14a.

Attached to the underside of the skate and particularly to the straps 17 and 19, is an illuminating device 20, in the form of a flashlight.

The device 20 comprises a clamp 21. Said clamp 21 comprises a longitudinal strip 22. At each end of the strip 22 are upwardly extending clamping hooks or fingers 23 and 24. The clamping hooks or fingers 24 may each be provided with an upwardly and outwardly extending finger engaging handle portion 25. Members 23 and 24 are in the form of hooks which may be hooked onto opposite edges of straps 17 and 19.

The handle portions 25 may be grasped and pulled or pushed to release or engage the clamp 21 relative to the skate. Attached to the underside of strip 22 at each end thereof, is a spring clip 30. Each spring clip 30 comprises a top portion 31, which may be fixed to the strip 22 in any suitable manner. Extending from each portion 31 are a pair of symmetrically disposed curved spring fingers 32.

It will be noted that one pair of clamp members 23 and 24 may be attached to strap portion 17, while the other pair of clamp members or hooks 23 or 24 may be attached to the other strap member 19. As shown in Fig. 1, the fingers 23, 24 may be pulled up and bent in shape required to engage the inclined straps 17, 19.

While the illuminating device is shown in the drawing herein, as being attached to the underside of a roller skate having downwardly and outwardly inclined portions for engagement with

the clamp fingers 23, 24, it will be understood that the clamp 21 may be attached to the underside of other types of roller skates or of ice skates.

Removably mounted on the clamp member 21 is a flashlight device 35. Said device comprises a casing 36 in the form of a cylindrical tube. Screwed to one end of the tube 36 is a closure member 36a. At the other end of the tube 36 is a downwardly and forwardly inclined socket 37, into which may be screwed the base 38 of a flashlight lamp 39. Within the casing 36 is a dry battery or cell 40. Interposed between the battery 40 and the closure member 36a is a coil compression spring 41, which presses the anode 42 of the battery into engagement with the central contact 43 carried by the lamp base 39.

In Figs. 5 and 6, the illuminating means 29 is shown attached to a roller skate or other skate having a horizontal strip 50 attached to members 14a beneath strip 12a. The attaching clips 23, 24 are engaged with strip 50 to mount the device 20 on the skate.

It will now be understood that the front and rear ends of the battery casing are gripped by the spring fingers 32. The casing 36 is thus carried in horizontal position, whereas, the lamp 39 projects forwardly and downwardly to thereby illuminate an area below and forwardly of the skate. The battery casing may be readily removed from the clamp, and the clamp may also be relatively easily removed from the skate. Furthermore, the clamp may be attached to various types of skates.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described our invention, we claim as new and desire to secure by Letters Patent:

1. In combination with a skate including a platform, front and rear axle supports, and a brace extending longitudinally under said platform between the axle supports; a carrier comprising a strip extending longitudinally under said brace, pairs of arms extending upwardly

from opposite side edges of opposite ends of said strip and having upper end portions bent inwardly and forming hooks extending inwardly across the upper surface of said brace from opposite side edges thereof and holding the arms in supported engagement with the brace, one arm of each pair having its hook-forming portion of greater length than the other and bent to form an upwardly and outwardly extending handle, and resilient straps secured across under faces of said strip and having end portions bent downwardly and forming longitudinally curved clamping jaws disposed under said arms in position to engage about portions of an article and suspend the said article under the strip longitudinally thereof.

2. In combination with a skate including a platform, front and rear axle supports, and a brace extending longitudinally between the axle supports; a carrier comprising a strip extending longitudinally under said brace and of less length than the brace, pair of arms extending upwardly from opposite side edges of opposite ends of said strip and having inwardly extending hooks at their upper ends overlapping the upper face of the strip from opposite side edges thereof, one arm of each pair having its hook provided with an upwardly extending handle, and clamps carried by said strip and having jaws extending downwardly therefrom in position to grip and hold an article between them.

ARTHUR WOODARD.
IRVING WM. LEWINE.
